CLAIM

The ornamental design for a combined bottle and can opener as shown and described.

DESCRIPTION

FIG. 1 is a perspective view illustrating the combined bottle and can opener;

FIG. 2 is another perspective view thereof;

FIG. 3 is a front view thereof;

FIG. 4 is a back view thereof;

FIG. 5 is a side view thereof;

FIG. 6 is another side view thereof;

FIG. 7 is a top view thereof; and,

FIG. 8 is a bottom view thereof.
